ARCH SUPPORT

Filed Sept. 25, 1945

INVENTOR.
PRENTIS E. ERICKSON
BY
R. A. Whitley
ATTORNEY

main supporting part above referred to, slidably contacting both the forward part of the main supporting member and the inner sole surface of the shoe.

It is a further object of my invention to rigidly attach the bridging member to the heel part of the main supporting member so that the yield and slide of the free end of the bridging member will be between the inner surface of the shoe sole and the part of the main supporting member toward the front of the shoe.

It is a further object of my invention to attach to the bridging member at or toward its front a spring member which is turned backwardly and which is adapted to press the supporting member toward the ball of the foot at or near the front part of the under instep to cause the front part of the main supporting member to be pressed inwardly with a yielding spring pressure to make complete contact with that part of the sole of the foot.

The full objects and advantages of my invention will appear in connection with the detailed description thereof and the novel features of the invention which produce the above-indicated advantageous results will be particularly pointed out in the claims.

In the drawings illustrating an application of my invention in one of its forms:

Fig. 1 is a side elevation view in section through a shoe as worn with a foot indicated in dotted lines showing the position of the parts of my invention.

Fig. 2 is a plan view of the arch support viewed from the outside thereof or toward the bottom of the foot as worn.

Fig. 3 is a longitudinal sectional view taken through the arch support alone on line 3-3 of Fig. 2.

Fig. 4 is a view similar to Fig. 3 showing the arch support twisted transversely across its width.

Fig. 5 is a schematic view illustrating how the parts of the supporting member may be relatively twisted laterally to adjust themselves to the conformation of the under side of the foot.

As shown, the arch support proper comprises a foot-contacting member 10 suitably shaped as indicated in Fig. 2 which is formed of some flexible material shaped generally to fit the sole of the foot between or over the heel and the ball of the foot. This shape gives a narrower part 11 adapted to come over the heel, a curved portion at 12 which fits inside of the small toe edge of the foot and an expanded portion 13, which extends toward the wider part of the foot adjacent or short of the ball of the foot. The flexible material of which the contact member is formed will be preferably of soft and yielding leather, although other flexible materials such as fairly heavy canvas could be employed.

Upon the outside or non-contacting side of the foot-contacting member 10 is secured by rivets or other fastening means 14 and 15 a spring-like supporting member 16, which has in general the outer contours of the flexible contact member 10, including the upward bulge indicated at 17 in Fig. 1.

This member is shaped as if it were a single member and has in general a curvature next to the contact member 10 similar along broad lines to the longitudinal and transverse curvature of the sole of the foot. It is made of spring steel so that it possesses a quality of spring yielding

which tends to adapt it to fit the bottom of the feet.

I do not, however, make the member 16 in a single continuous piece but I divide it at 18 transversely across the steel supporting member 16 so as to provide two parts, a rear part and a forward part. The rear part is designated as 19 and is the part which comes under the heel of the foot. The forward part is designated as 20 and comes under the part of a foot extending substantially from the instep to or near the ball of the foot.

Rigidly secured by rivets or otherwise to the rear part 19 of the supporting plate 16 is a spring member 21. This spring member curves upwardly and then downwardly, as clearly indicated in Fig. 1, and engages with its forward end 22 the inner surface of the sole 23 of the shoe in which it is worn.

This spring member 21 is unattached at its forward end and is adapted to slide at its edge 24 upon the surface of forward part 20 of supporting plate 16. The spring member 21 will preferably be roughly hour-glass shaped as shown in Fig. 2, and it bridges the line of division 18 at its narrow point, indicated at 25.

In one form of the invention a spring plate 26 is rigidly attached at 27 to the front end of the bridging member 21, being turned backwardly to engage the part 20 of the supporting plate 16 and tend to push that part against the hollowed-cut portion of the under side of the sole of the foot, as clearly shown in Fig. 3. This is made possible because the supporting spring plate 16 is divided at 18, permitting a hinging action there.

The parts 19 and 20 substantially engage each other along the line of division 18 toward the center thereof, but are slightly separated at their sides as indicated at 28 and 29, as clearly shown in Fig. 2.

The effect of this arrangement is, of course, to permit direct hinging movements of the two parts 19 and 20 of the supporting plate 16 upon their regions of contact at the point 25. It also permits lateral rocking movements of the parts 19 and 20 upon the same point of contact, and further, and perhaps most important of all, provide freedom for lateral twisting movements upon the same point of contact.

The advantages of my invention will sufficiently appear from a consideration of the foregoing description and objects of the invention. The great and fundamental advantage resides in the fact that the arch support is capable of hinging and twisting lateral adjustments at and across the center of the arch supporting plate, thus taking care of variances and differences in the under side of feet due to the differences in the essential bony structure forming a support for the soft parts of the foot.

These lateral adjustments made in relation to the underlying bony structure are of the highest importance in making the wearing of the arch support comfortable and in correcting the abnormalities and deficiencies of flat feet.

A further advantage comes from the fact that the arrangement of a spring member or spring members under the divided arch supporting plate is such as to distribute the supporting stresses to the regions on the under side of the foot in a manner best to effect the transmission of supporting stresses to the bony structure of the foot.

I claim:

1. An arch support, comprising a foot-contacting member formed of material which can flex both longitudinally and transversely such as leather so as to twist transversely to conform to the varying relative shapes of the heel and front parts of the foot, and a spring plate formed in two parts by a transverse division and having each of the parts secured to the member so the parts will contact along the line of division and may twist freely to adjust themselves laterally to the conformation of the bony structure of the foot.

2. An arch support, comprising a foot-contacting member formed of material which can flex both longitudinally and transversely such as leather so as to twist transversely to conform to the varying relative shapes of the heel and front parts of the foot, and a spring plate formed in two parts by a transverse division and having each of the parts secured to the member, said division being formed with curved end portions on each of the parts so as to bring contact of the parts between central longitudinal planes of the plate and to permit the parts to rock laterally for adjusting the same to the foot and to the bony structure thereof.

3. An arch support, comprising a foot-contacting member formed of material which can flex both longitudinally and transversely such as leather so as to twist transversely to conform to the varying relative shapes of the heel and front parts of the foot, and a spring plate formed in two parts by a transverse division and having each of the parts secured to the member so the parts will contact along the line of division and may twist freely to adjust themselves laterally to the conformation of the bony structure of the foot, and a spring member secured to one of said parts, said spring member to contact the shoe and to have sliding contact to the other of said parts thus bridging over the division of the plate.

4. An arch support, comprising a foot-contacting member formed of material which can flex both longitudinally and transversely such as leather so as to twist transversely to conform to the varying relative shapes of the heel and front parts of the foot, a spring plate formed in two parts by a transverse division and having each of the parts secured to the member so the parts will contact along the line of division and may twist freely to adjust themselves laterally to the conformation of the bony structure of the foot, and a spring member secured to one of said parts, said spring member to contact the shoe and to have sliding contact to the other of said parts thus bridging over the division of the plate, said spring member being narrowed at its center where it overlies the division between said parts and broadened at its plate-contacting end.

5. An arch support, comprising a foot-contacting member formed of material which can flex both longitudinally and transversely such as leather so as to twist transversely to conform

to the varying relative shapes of the heel and front parts of the foot, a spring plate formed in two parts by a transverse division and having each of the parts secured to the member so the parts will contact along the line of division and may twist freely to adjust themselves laterally to the conformation of the bony structure of the foot, a spring member secured to one of said parts, said spring member to contact the shoe and to have sliding contact to the other of said parts thus bridging over the division of the plate, and a second spring member secured to the free end of the first named spring member and extending rearwardly therealong and bent to engage the surface of the part over which the free end of the spring member slides.

6. An arch support, comprising a flexible foot-contacting member, a spring plate formed in two parts by a transverse division, said plates jointly forming with the member a continuous longitudinally extended arch, one of said plates extending toward the heel part and the other plate toward the ball part of the foot, and a spring member secured at one end to the heel part and slideable at its other end over the ball part, said spring member being arched downwardly so as to tend to lift the heel part with a spring action and twist freely to permit lateral adjustment movements of the ball part.

7. An arch support, comprising a flexible foot-contacting member, a spring plate formed in two parts by a transverse division, said plates jointly forming with the member a continuous longitudinally extended arch, one of said plates extending toward the heel part and the other plate toward the ball of the foot, a spring member secured at one end to the heel part and arched upwardly and then downwardly so as to contact at its front end the sole of the shoe and effect an upward yielding pressure upon the rear part, and a second spring member attached to the front of the first named spring member and extending rearwardly to engage the front part of said plate to give a springing upward lift to said front part, the arrangement of the two parts and of the two spring members being such as to permit hinging movements and lateral twisting movements of the two parts.
